US0D1069076S

(12) **United States Design Patent** (10) Patent No.: **US D1,069,076 S**
(45) Date of Patent: ** Apr. 1, 2025

(54) **AIR PURIFIER**

(71) Applicant: **Shenzhen Chenbei Technology Co., Ltd.**, Shenzhen (CN)

(72) Inventors: **Liang Wang**, Shenzhen (CN); **Weiyu Zheng**, Shenzhen (CN); **Alex William Chow**, Anaheim, CA (US)

(**) Term: **15 Years**

(21) Appl. No.: **29/871,045**

(22) Filed: **Feb. 10, 2023**

(30) **Foreign Application Priority Data**

Aug. 11, 2022 (CN) 202230522741.1

(51) **LOC (15) Cl.** **23-04**

(52) **U.S. Cl.**

USPC **D23/364**

(58) **Field of Classification Search**

USPC D23/355, 357, 361, 362, 363, 364, 365, D23/366, 368, 369

CPC . F24F 8/10; F24F 8/80; F24F 2110/50; B01D 45/12; B01D 45/14

(57) **CLAIM**

The ornamental design for an air purifier as shown and described.

DESCRIPTION

FIG. 1 is a perspective view of an air purifier showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the air purifier that form no part of the claimed design.

1 Claim, 7 Drawing Sheets
